Primary Examiner — Tracey J Bell(74) *Attorney, Agent, or Firm* — Law Office of Michael O'Brien; Michael O'Brien(57) **CLAIM**

The ornamental design for a spray bottle with belt clip, as shown and described.

DESCRIPTION

FIG. 1 is a front perspective view of a new design for a spray bottle with belt clip.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the spray bottle with belt clip that form no part of the claimed design.

1 Claim, 7 Drawing Sheets(56)
